UNITED STATES PATENT OFFICE

RUDOLPH WEHR, OF LOS ANGELES, CALIFORNIA, ASSIGNOR TO THE WEHR MOTOR COMPANY, A CORPORATION OF CALIFORNIA

VALVE CONSTRUCTION

Application filed April 15, 1929. Serial No. 355,062.

My invention relates to internal combustion engines, and more particularly to the valve construction associated therewith in which means are provided for compensating for temperature and wear changes to which said valve is subjected to the end that leakage between the inlet and exhaust ports will effectively be prevented.

It accordingly is an object of my invention to provide a novel form of packing shoes for continually urging the rotary valve into contact with its casing to compensate for temperature and wear changes, each of said shoes being also provided with means whereby un- even wear thereof will effectively be obviated, and buckling of said shoes will be prevented.

A further object of my invention is to position the rotary valve of an internal combustion engine in its casing so that a line of contact between the inlet and cylinder ports of less than 180 degrees will be continually maintained between the periphery of said valve and its casing, packing means for accomplishing this being also associated with said valve.

The above and further objects and advantages of my invention, as will hereinafter more fully appear, I attain by the construction described in the specification and illustrated on the drawings forming a part of my application.

Reference is had to the accompanying drawings, in which similar reference characters denote similar parts. In the drawings, Fig. 1 is a cross-sectional view through the valve casing showing my novel form of packing shoes,

Fig. 2 is a top plan view of the upper packing shoe,

Fig. 3 is a cross-sectional view taken in the line 3—3, Fig. 2,

Fig. 4 is a bottom plan view of the lower packing shoe,

Fig. 5 is a side elevational view of the packing means for the slots in the lower shoe, and

Fig. 6 is a more or less fragmentary diagrammatic cross-sectional view illustrating in an exaggerated way the position of the valve with respect to its casing.

Describing my invention more in detail,

it sometimes happens that the packing shoes associated with the rotary valve of an internal combustion engine are inaccurately machined, and in consequence may be subjected to buckling, it accordingly is one of my objects to provide said shoes with a means whereby this objectionable feature may be effectively prevented.

It is, moreover, a desideratum that an accurate line of peripheral contact between the valve and its casing be continually maintained between the inlet and cylinder ports, and to this end I so position the valve in its casing that there will be a continual line contact of less than 180 degrees between the valve and its casing.

More specifically, the valve casing 2, is equipped with an inlet port 4 and an exhaust port 6, the rotary valve 8 being adapted periodically to control said ports and the cylinder port 10, said valve being so positioned relatively to the casing 2 that there will be a peripheral line contact between said casing of less than 180 degrees to the right thereof, to insure that there will be no leakage from the inlet to the exhaust, a small clearance space 12, shown in exaggerated form in Fig. 6, being provided to the left of the valve and casing.

To this end, the axis of the valve 8 is positioned slightly offset with respect to the axis of the valve casing, and the shoes 14 and 16 coact to push said valve toward the right in Fig. 6, when the valve is rotated as indicated by the arrow in Fig. 1. This causes a continuous line contact of the periphery of the valve 8 with the inner valve casing wall beginning with a point substantially from the left of the port 10 to a trifle less than one-half the inner surface of the shoe 16; in other words, less than 180°, thus permitting the port 10 to be centrally positioned with respect to the cylinder of the engine.

To continually urge the valve 8 to the eccentric position shown in Fig. 6, and to compensate for temperature and wear changes, I provide a pair of relatively slidable packing shoes 14 and 16, maintained in continual sliding engagement with each other and with the valve 8, which shoes are held in

such engagement by means of the adjustable spring construction 18.

In practice it sometimes happens that the shoes 14 and 16 are improperly machined, and accordingly are subjected to uneven wear and buckling. To prevent this I provide the upper shoe 14 with the cut-away or cut-out portions 20, which effectively prevent the ends of said shoe from curling upward, a passage 22 being provided for introducing a lubricant between the shoes 14 and 16. It will, of course, be understood that the character and depth of cut of said cut-away or cut-out portions may be any that in practice is required.

To prevent uneven wear and buckling on the lower shoe 16, I make said shoe more elastic by providing at least one slot or groove 24 on the lower valve engaging surface thereof, and in said slot or groove, I position the packing member or means 26 (Fig. 5), which is preferably constructed of a heat non-conducting material, such as asbestos or asbestos composition.

In operation, the valve being rotated in the direction of the arrow shown in Fig. 1, the spring construction 18 will continually urge the shoes 14 and 16 into sliding engagement, the shoe 16 being held in continual engagement with the valve 8, which is held in peripheral line contact with the inner wall of the casing 2, said line contact being less than 180 degrees, to insure that there will be no leakage between the inlet and exhaust ports, a small clearance space 12 being thus provided between the left portion of the casing and the valve. The cut-away or cut-out portions 20 in the shoe 14, and the grooves or slots 24, as hereinbefore stated, preventing effectively uneven wear and buckling.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. In a valve construction in combination with a rotary valve, of a pair of relatively movable packing shoes for compensating for temperature and wear changes, to which said valve is subjected, each of said shoes being provided with freely movable means unconnected to said valve casing for rendering one of said shoes more elastic, whereby the wear due to inaccurate machining will be compensated for.

2. In a valve construction, in combination with a rotary valve, of a pair of relatively slidable packing shoes for compensating for temperature and wear changes to which said valve is subjected, one of said shoes being

provided with cut-away portions, and the other with at least one slot, to prevent each of said shoes from buckling.

3. In a valve construction, in combination with a rotary valve, of a pair of relatively slidable packing shoes for compensating for temperature and wear changes to which said valve is subjected, one of said shoes being cut out on the top portion thereof, and the other provided with at least one slot, to prevent each of said shoes from buckling, and packing means in each of said slots.

4. In a valve construction, in combination, a valve casing, a valve adapted for rotation in said casing, said valve being eccentrically positioned in said casing that a line of contact will be continually maintained between said valve casing and said valve, between the inlet port of said casing and the cylinder port controlled by said valve, and packing means for continually urging said valve into said contact.

5. In an internal combustion engine, in combination, a valve casing, a rotary valve in said casing, said valve being eccentrically positioned in said casing that a line of contact will be continually maintained between said valve and said casing between the inlet port of said casing and the cylinder port controlled by said valve, said line of contact being less than one hundred and eighty degrees, and packing means for continually urging said valve into said contact.

6. In a valve construction, a valve casing, a rotary valve in said casing, said valve being eccentrically positioned in said casing so said valve will be in continual engagement with said casing for less than one hundred and eighty degrees of its periphery, and means for continually urging said valve into said engagement.

7. In a valve construction, a packing shoe provided with at least one groove for preventing buckling when said shoe is used in connection with the rotary valve of an internal combustion engine.

8. In a valve construction, a packing shoe provided with at least one slot for preventing uneven wear and buckling when said shoe is used in connection with the rotary valve of an internal combustion engine, and a packing member in said slot.

In testimony whereof I have signed my name to this specification.

RUDOLPH WEHR.
